[57] CLAIM

The ornamental design for an eyeglass frame, as shown
and described.

DESCRIPTION

FIG. 1 is a front elevational view of an eyeglass frame
showing my new design;

FIG. 2 is a rear elevational view thereof;

FIG. 3 is a left side elevational view thereof, the right
side being a mirror image;

FIG. 4 is a top plan view thereof; and,

FIG. 5 is a bottom plan view thereof.

FIG. 1

FIG. 2

FIG. 3

FIG. 4

FIG. 5
